UNITED STATES PATENT OFFICE.

KARL M. HAMILTON, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CAR END FRAME.

1,355,331.

Specification of Letters Patent. Patented Oct. 12, 1920.

Application filed October 22, 1919. Serial No. 332,413.

To all whom it may concern:

Be it known that I, KARL M. HAMILTON, a citizen of the United States, residing in Chicago, in the county of Cook and State of Illinois, have invented a new and useful Improvement in Car End Frames, of which the following is a specification.

The invention relates to refrigerator cars and principally to a frame construction for the ice compartment, said frame being strongly united and made unitary with the end frame of the car and with the partition which separates the ice compartment from the freight compartment of the car.

An object and result of the improvement are that the body of ice is properly supported and confined and the racking of the car frame sheathing and partition is prevented, so that the durability of the frame and car body generally is greatly increased.

With such object in view, as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:

Figure 1 is a vertical longitudinal section of the end portion of a car body, showing portions of the frame and taken through the ice compartment on line 1—1 of Fig. 2.

Fig. 2 is a plan view of the same with the top sheathing and some of the frame members removed.

Fig. 3 is a vertical transverse section of the roof portion of the car on line 3—3 of Fig. 2, but showing slight modifications of the car structure.

Fig. 4 is a vertical transverse section of the eaves portion of the car on line 4—4 of Fig. 2.

Fig. 5 is a vertical longitudinal section of

an upper end portion of the car on line 5—5 of Fig. 2.

Fig. 6 is a vertical longitudinal section of an upper portion of the car on line 6—6 of Fig. 2.

Referring to the drawings, the car frame as illustrated comprises center sills 1, end sills 2, side sills (not shown), side plates 3 of the roof frame, end plates 4, carlines 5, side sheathing 6, end sheathing 7, top sheathing 8, side fascia 9 and end fascia 10. These parts are or may be of usual or suitable construction. The floor 11 is supported by the bottom frame members and is formed with air spaces 12 which are non-conductive of heat.

The ice and freight compartments are indicated generally by the numerals 13 and 14, the latter extending to the other end of the car (not shown), or to the other ice compartment in case the car be provided with one of the same at each end. These compartments are partly separated by a partition 15 having upper and lower air circulation openings 16 and 17.

The frame of the ice compartment is or may be constructed as follows: 18, 19 indicate horizontal transverse frame members extending across the car at the top of the ice compartment, the member 18 being secured to the end plate 4 by bolts 20, and the member 19 being at the inner side of the ice compartment substantially over the partition 15 and attached and supported independently of the car side frame.

21 indicates longitudinal frame members arranged one at each side of the median line of the car and bolted or riveted at their ends at 22 to said transverse members 18 and 19. The frame further comprises longitudinal side members 23 which are arranged inside of the side frame and sheathing of the car and independent thereof and are bolted or riveted to said transverse members at 24. The above described frame members are of convenient structural shape, bars of L-shape being illustrated. 25 indicates a horizontal reinforcing bracket plate having its ends arranged at the intersection of the bars 21 with the bar 18 and to extend from one to the other and connecting said intersections, this bracket plate being riveted to the bars 21 at 26 and to the bar 18 at 27, and it is also preferably perforated to receive the

rivets 22. 28 indicates corner bracket plates arranged at the intersections of the bars 23 with the bar 18 and riveted to the former at 29 and to the latter at 30, being also preferably 5 perforated to receive the rivets 24. 31 indicates horizontal bracket plates arranged at the intersection of the bars 23 with the bar 19 and riveted to the former at 32 and to the latter at 33, being also preferably 10 perforated to receive the rivets 24. 34 indicates horizontal bracket plates, shown in dotted lines in Fig. 2, arranged at the intersection of the bars 21 with the bar 19 and riveted to the former at 35 and to the latter at 36, being also preferably 15 perforated to receive the rivets 22.

The bars 23 are extended for a considerable distance inward from the transverse bar 19 and their ends are strongly connected 20 and braced with the middle portion of the said frame by horizontal diagonal bars 37 which are riveted at 38 to the bars 23 and which cross one another and are riveted at 39 to the bars 21. Except for these last 25 connections bars 37 may be free from the middle portion of the said frame, or they may be perforated to receive the rivets 36 or other rivets which are in line with them.

At the outer side of the end of the car are 30 vertically arranged Z-bars 40 which extend from the end plate 4 to the end sill 2 and are strongly united thereto. The securing of the upper ends of these Z-bars is illustrated by the bolts 41 (Fig. 1) which pass 35 through them and through the end plate 4. Certain of said bolts 41 also pass through the transverse bar 18 and make the same rigid with the end plate and with the end frame of the car generally.

40 While the braced frame above described does not derive its strength and lateral stiffness from the side frame elements of the car, it may be connected therewith as by bolts 42 (Figs. 1 and 4) which pass through 45 the side bars 23 and through the side frame members of the car body.

The said frame is supported from below by suitable vertical posts 43 rising from the bottom frame of the car body, and to said 50 posts are attached horizontal cross bars 44 and to the latter vertical slats 45 to form a grating to keep the cakes of ice in position. The ice is supported upon a bottom grid 46 at a suitable distance above the floor of the 55 car. 47 is an opening into the car roof leading into the compartment 13 through which ice may be charged into the latter, (Fig. 3). The vertical boards forming the opening 47 or may be supported by the elements 21 and 23 as seen in Fig. 3, and also by the frame elements 18 and 19 if desired.

60 The upper part of the car body is preferably cut off as an air chamber by a sub-sheathing 48. An inner side sheathing 49 forms non-conducting air spaces 50 in the

sides of the car. The top of the compartment 13 is provided with a suitable sheathing 51, which may be double as shown in Fig. 5, forming an additional non-conducting air space 52; and the end wall of the 70 compartment 13 is formed by a suitable inner end sheathing 53.

The frame comprising the elements 18, 19 etc., is in itself stiff and rigid in horizontal planes. When it is attached to side members 75 of the car frame it renders stiff and holds from distortion the car body.

What is claimed is:

1. A refrigerator car body provided at the end with an ice compartment, said compartment having a horizontal braced frame of skeleton structure, extending transversely of the car and securely attached to the end frame of the car and sustaining the inner partition of said compartment against horizontal strains imposed by the body of ice within the same. 80

2. A refrigerator car body provided at the end with an ice compartment, said compartment having a horizontal braced frame 90 of skeleton structure, extending transversely of the car and securely attached to the end frame of the car and sustaining said compartment against horizontal strains imposed by the body of ice within the same, said braced frame being attached to and sustained by the end frame of the car. 95

3. In a refrigerator car a vertical partition forming an ice compartment at the end of the car, and a horizontal braced frame 100 of skeleton structure, extending transversely of the car and connecting said partition rigidly with the end frame of the car.

4. In a refrigerator car the combination of longitudinal bars connected with the end frame of the car and extending inward within the car body near the sides of the same, a horizontal transverse bar attached to said longitudinal bars and attached to the end frame of the car, a horizontal transverse bar arranged at a distance from the ends of the car and attached at its ends to said longitudinal bars, longitudinal bars arranged near the middle of the car and attached to said transverse bars bracing bars attached to the rear ends of the first mentioned longitudinal bars and attached at their other ends to said longitudinal bars which are near the middle of the car, and an ice sustaining partition arranged at a distance from the end 110 of the car and connected with the frame formed by the above described system of bars. 115

5. In a refrigerator car, the combination of vertical Z-bars arranged at the outside of the end of the car near the middle thereof, a horizontal transverse bar within the end of the car and securely attached to said Z-bars, and a horizontal braced frame carried by said horizontal bar and comprising an 120 130

inner transverse bar and extending inward within the body of the car, and an ice sustaining partition arranged at a distance from the end of the car and connected with 5 said braced frame.

6. In a refrigerator car, the combination of a frame comprising an outer horizontal transverse bar within the end of the car and securely attached to the car end, outer longitudinal bars attached to said outer transverse bar and extending inwardly at the sides of the car, an inner transverse bar attached to said outer longitudinal bars at points between the inwardly extended ends 10 of the same and said outer transverse bar, inner longitudinal bars attached to both of said transverse bars, and bracing bars attached to the extended ends of said outer longitudinal bars and crossing each other 15 and attached to said inner longitudinal bars, and a partition arranged at a distance from the end of the car and connected with said frame. 20

7. In a refrigerator car, the combination 25 of vertical bars arranged on the outside of the car end, a frame comprising an outer horizontal transverse bar within the end of the car and securely attached to said vertical bars, outer longitudinal bars attached 30 to said outer transverse bar and extending inwardly at the sides of the car, an inner transverse bar attached to said outer longitudinal bars, inner longitudinal bars attached to both of said transverse bars, and bracing bars attached to the said outer longitudinal bars and crossing each other and attached to said inner longitudinal bars, and a partition arranged at a distance from the 35 end of the car and connected with said frame. 40

8. In a refrigerator car, the combination 45 of vertical Z-bars arranged on the outside of the car end, a frame comprising an outer horizontal transverse bar within the end of the car and securely attached to said Z-bars, outer longitudinal bars attached to said outer transverse bar and extending inwardly at the sides of the car, an inner transverse 50 bar attached to said outer longitudinal bars, and a partition arranged at a distance from the end of the car and connected with said frame. 55

bar attached to said outer longitudinal bars, inner longitudinal bars attached to both of 50 said transverse bars, and diagonal bracing bars attached to said outer longitudinal bars and attached to said inner longitudinal bars, and a partition arranged at a distance from the end of the car and connected with said 55 frame.

9. In a refrigerator car, the combination 60 of vertical Z-bars arranged on the outside of the car end, a frame comprising an outer horizontal transverse bar within the end of the car and securely attached to said Z-bars, outer longitudinal bars attached to said outer transverse bar and extending inwardly at the sides of the car, an inner transverse bar attached to said outer longitudinal bars 65 at points between the inwardly extended ends of the same and said outer transverse bar, inner longitudinal bars attached to both of said transverse bars, and bracing bars attached to the extended ends of said outer longitudinal bars and attached to said inner longitudinal bars, and a partition arranged at a distance from the end of the car and connected with said frame. 70

10. In a refrigerator car, the combination 75 of vertical Z-bars arranged on the outside of the car end, a frame comprising an outer horizontal transverse bar within the end of the car and securely attached to said Z-bars, outer longitudinal bars attached to said 80 outer transverse bar and extending inwardly at the sides of the car, an inner transverse bar attached to said outer longitudinal bars at points between the inwardly extended ends of the same and said outer transverse 85 bar, inner longitudinal bars attached to both of said transverse bars, and bracing bars attached to the extended ends of said outer longitudinal bars and crossing each other and attached to said inner longitudinal bars, 90 and a partition arranged at a distance from the end of the car and connected with said frame.

In testimony whereof I have hereunto set my hand.

KARL M. HAMILTON.
